ELECTRON BEAM CONVERGENCE APPARATUS

John C. Cooper, Lititz, and Robert W. Hagmann, Lancaster, Pa., assignors to Radio Corporation of America, a corporation of Delaware

Application October 30, 1956, Serial No. 619,197

7 Claims. (Cl. 315—13)

The present invention relates to apparatus for controlling the electron beams of a cathode ray tube and, particularly, to a system in which a plurality of electron beams is deflected by a common deflection apparatus.

One type of cathode ray tube with which the present invention may be successfully employed is a color kinescope of the general type described in an article entitled "Development of a 21" Metal-Envelope Color Kinescope," by Seelen et al., published in the RCA Review for March 1955, at page 122. Such a tube has a luminescent screen as part of a target electrode structure and in which different phosphor areas produce differently colored light when excited by electron beam components impinging upon the target structure from different angles, the angle of impingement determining the particular color of the light produced by the phosphor areas.

It is necessary for the satisfactory operation of such kinescopes to effect substantial convergence of the different electron beams at all points of the raster scanned thereby at the target electrode structure. In general, the matter of beam convergence is discussed in an article entitled "Deflection and Convergence in Color Kinescopes" by A. W. Friend, Proceedings of the IRE, October 1951, at page 1249. One type of apparatus for controlling the convergence of a plurality of electron beams at a target electrode structure and with which the present invention is particularly concerned comprises, in general, individual electromagnetic means located respectively adjacent to the predeflection paths of the respective beams and of such character as to be energizable from the beam deflection circuits in a manner to effect the desired beam convergence.

A particular electromagnetic beam convergence means to which this invention pertains includes, for each beam, a pair of pole pieces located internally of the kinescope envelope. The internally located pole pieces are energized by magnetic apparatus located externally of the kinescope and associated, respectively, with the different pairs of pole pieces. The convergence pole pieces require, in general, energization both statically and dynamically, the latter energization being in accordance with a function of the angles through which the electron beams are deflected.

Prior arrangements for effecting static convergence of a plurality of beam components have included means for separately energizing each convergence structure with an adjustable direct current energy so that, in order to converge a plurality of beams at the center of the target electrode or other selected point, each beam must be individually moved radially to its desired position. It will be appreciated that, in a three-beam kinescope of the type described, this procedure, which may be termed a "radial convergence," is time-consuming and requires painstaking care, since three separate controls must be adjusted.

It is, therefore, an object of the invention to provide new and improved apparatus for effecting convergence

2

of a plurality of electron beam components in a multiple beam kinescope.

Another object of the invention is to provide improved apparatus for statically energizing the several structures under the control of which several electron beam components are converged at substantially the target electrode structure of a color kinescope.

In accordance with an illustrative embodiment of the present invention as it may be applied to a color kinescope of the type set forth, static convergence of three electron beams is effected by the application of suitable direct current energy to two of the beam converging structures via dual beam control means which are so arranged that the two beams controlled thereby may be moved simultaneously toward each other until converged, the relative amplitudes of the static energy applied to them being controlled. The third beam controlling structure is adjustably energized from a separate source which may then be employed to move that beam into convergence with the two first-named beams. As will appear more fully hereinafter, the movement of the beams in accordance with the invention is in the nature of a "rectangular coordinate" movement.

By virtue of the rectangular coordinate nature of the present apparatus, the time required for effecting static convergence of a multi-beam kinescope is greatly reduced and the procedure itself is simplified over prior art arrangements.

According to another aspect of the present invention, means are provided for cross-feeding certain of the convergence energy employed in moving the third-recited beam to the structures which control the first two beams, whereby adjustment of the third beam does not necessitate readjustment of the dual beam controls.

Additional objects and advantages of the present invention will become apparent to those skilled in the art from a study of the following detailed description of the accompanying drawing, in which:

Figure 1 illustrates a cathode ray tube convergence system in connection with which the present invention is to be described;

Figure 2 is a vertical sectional view taken along line 2—2 of Figure 1; and

Figures 3 and 4 are schematic diagrams of circuits for energizing the convergence magnets of Figures 1 and 2.

Reference will first be made to Figure 1 of the drawing for a general description of an illustrative embodiment of an electron beam convergence system in accordance with the present invention. The system includes a color kinescope 11 which may be of the same general type as that disclosed in the Seelen et al. article referred to above. The kinescope has a luminescent screen 12 provided with a multiplicity of small phosphor areas arranged in groups, the areas of each group being capable respectively of producing light of different component colors in which the image is to be reproduced in response to electron impingement. In back of and spaced from the screen 12 is an apertured masking electrode 13 having an aperture for and in substantial alignment with each group of phosphor areas of the screen 12. It will be noted that both the luminescent screen and the masking electrode have generally spherical surfaces which are substantially concentric. It is to be understood, however, that the present invention is equally applicable to other forms of target electrode configuration.

In the particular case illustrated, the kinescope also has a plurality of electron guns, equal in number to the number of component colors in which the image is to be reproduced. Each of these guns may be conventional, consisting of a cathode, a control grid and a focusing electrode. Since the three guns are identical, the dif-

ferent parts thereof will be referred to collectively as the cathodes 14, the control grids 15, and the focusing electrodes 16. The three electron guns produce schematically represented electron beams 17, 18 and 19 by which to energize, respectively, the blue, red and green phosphor areas of the screen 12. When these electron beams are properly converged at the target electrode structure including the screen 12 and the masking electrode 13, they pass through the apertures of the masking electrode from different directions and impinge upon different phosphor areas of the various groups so as to produce blue, red and green light. It is to be noted that the size of the phosphor areas, the angles between the beams and the spacing of the mask 13 from the screen 12 as compared with the length of the tube are exaggerated for better illustration of this aspect of the kinescope.

The electron-optical apparatus of the kinescope 11 also includes a beam-accelerating electrode consisting, in the present instance, of a conductive wall coating 20 formed on the inner surface of the tubular glass neck 21 and the conical section 22 of the kinescope extending from the region adjacent to the outer end of the focusing electrodes 16 to the target electrode region. Preferably, the target electrode structure, including the masking electrode 13 and the luminescent screen 12, which for this purpose may be metallized, is electrically connected to the wall coating 20 by suitable conventional means (not shown). Metallization of a luminescent screen of the character described may be effected in the manner disclosed in a paper by D. W. Epstein and L. Pensak entitled "Improved Cathode Ray Tubes with Metal-Backed Luminescent Screens" published in the RCA Review, vol. VII, March 1946, at pages 5-10.

The described electrode structure of the kinescope may be energized in a conventional manner such as that illustrated. The source of energy is represented by a battery 23 across the terminals of which there is connected a voltage divider 24. The cathodes 14 are connected to the grounded point of the voltage divider and the control grids 15 are connected to a point which is somewhat negative relative to ground. Similarly, the focusing electrodes 16 are connected to a point on the voltage divider which may conventionally be at a potential of approximately 4,000 volts positive relative to the grounded cathodes. Also, the beam-accelerating anode, including the wall coating 20, is connected to the voltage divider 24 at a point which may conventionally be approximately 25,000 volts positive relative to the grounded cathodes.

The electron beams 17, 18 and 19 are modulated suitably in intensity under the control of color-representative video signals derived from a source 25. It will be understood that the video signal source is represented herein entirely diagrammatically since it does not per se form part of the present invention. The signal source 25 usually will be part of a signal receiver and may be understood to include a signal detector, or equivalent device, together with one or more stages of video signal amplification. Alternatively, the video signal source may be a color television camera in the event that the kinescope 11 is employed as a monitor, for example. Also, it will be understood that the illustrated connection of the video signal source 25 to the electron guns of the kinescope 11 is merely diagrammatic and accordingly these connections may or may not be made directly to the cathodes 14. Instead, it will be understood, that they may be made to the grids 15 or, in accordance with other modes of operation of color image-reproducing apparatus, the video signal source may be connected both to the cathodes and to the control grids of the electron guns.

Also associated with the color kinescope 11 is a deflection yoke 26 which may be entirely conventional including two pairs of suitably placed coils electrically connected together in such a manner that, when properly energized, electromagnetic fields are produced, whereby

to effect both horizontal and vertical angular deflections of the electron beams so as to scan the usual rectangular raster at the target electrode structure. Energization of the deflection coils comprising the yoke 26 may be effected by conventional vertical and horizontal deflection wave generators 27 and 28, respectively. Such apparatus will be understood to function suitably to produce substantially sawtooth wave energy at both horizontal and vertical deflection frequencies so that the fields produced by the yoke 26 are varied in a substantially sawtooth manner.

The beam convergence system with which the present invention is to be illustrated also includes a plurality of electromagnetic field-producing elements such as the electromagnets 29, 30 and 31 (see also Figure 2) mounted around the neck 21 of the color kinescope adjacent to the predeflection paths of the electron beams. It is to be understood that the precise location of these magnets is not necessarily indicated in Figure 1. Instead, it is to be understood that each of these magnets is located relative to one of the electron beams so as to influence its associated beam to the virtual exclusion of the others. Furthermore, it is to be understood that these magnets are of a character which, when suitably energized, produce respective fields which are transverse to the associated beam paths and in directions to move the associated beams radially relative to the longitudinal axis of the kinescope 11.

Each of these convergence electromagnets includes a generally U-shaped pole piece or core member and a pair of energizing windings. Two windings are or may be provided for each of the electromagnets for separate energization, as will be described subsequently in greater detail.

Before describing the details of the particular beam convergence system in accordance with the present invention, a brief description will be given of the general manner in which the apparatus functions to produce the desired results. The convergence magnets 29, 30 and 31 are energized, in one embodiment, by substantially unidirectional energy so as to effect an initial convergence of the electron beams substantially at the target electrode structure including the screen 12 and the apertured masking electrode 13. In order to do this, prior art systems have involved the separate unidirectional energization of these magnets in such manner that the magnets are individually energized in different magnitudes. The present invention, on the other hand, affords a simpler convergence system employing what has been termed herein a "dual control" system to be described in detail herein-after. In effecting this initial beam convergence, it is to be understood that, as in the case of prior art systems, the beams may be in any desired one of their different deflected positions. For example, they may be initially converged at the center of the raster to be scanned. Alternatively, they may be initially converged at one corner of the raster.

The convergence magnets 29, 30 and 31 are also dynamically energized by the control wave energy derived from suitable generators (shown in, and described subsequently with reference to, Figures 3 and 4) so as to effect a variation in the magnitude of the transverse fields produced respectively thereby. These field strength variations are in accordance with a predetermined function (usually approximately parabolic) of the angular beam deflection. Variations in the strength of the fields produced by the convergence magnets effect corresponding variations in the paths of the electron beam components relative to the longitudinal axis of the tube. Hence, suitable variations are made in the convergence angles between the various beam components so as to produce the desired convergence of the beam components substantially at the target electrode structure including the screen 12 and the masking electrode 13.

For a further description of this type of beam convergence apparatus, reference will now be made to Figure 2 of the drawings. This figure shows more clearly

the positions of the convergence magnets 29, 30 and 31 relative to one another and to the electron beams with which they are respectively associated. Inasmuch as all of these magnets are substantially the same, only one of them will be described in detail. The convergence magnet 29, which is associated with the blue electron beam 17, is provided with a core having two external pole pieces which are mounted so as to be in close association with the tube neck 21. The magnets may be mounted around the neck of the kinescope by any suitable means such as holders of insulating material which are sprung-urged together. The magnet also is provided with an energizing structure.

In Figure 2, it also is illustrated that for each of the convergence magnets there are provided on the inside of the tube neck 21 internal pole pieces so as to increase the effectiveness of these magnets. The magnet 29, for example, is provided with a pair of inwardly extending internal pole pieces 37 and 38, associated respectively with the external pole pieces. By such means, the reluctance of the magnetic circuit is considerably decreased, and also the flux distribution of the field produced between the internal pole pieces 37 and 38 is considerably improved.

Thus, the convergence magnet 29 effectively produces a field which, in the vicinity of the electron beam 17, is substantially transverse to the axis of the kinescope. By means of such a field, the electron beam 17 may be moved radially toward or away from the longitudinal tube axis, the direction and magnitude of such a beam movement being controlled by the energization of the magnet. The convergence magnets 30 and 31, respectively, control the electron beams 18 and 19 in a substantially similar manner.

The magnet 29 comprises a generally U-shaped pole piece 40 of ferrite or other suitable magnetic core material, the extremities of the legs of the U being located adjacent to the internally located pole pieces 37 and 38. Electromagnetic coils 41 and 42 for energizing the magnet 29 with a suitable waveform of television vertical or field frequency are wound about the legs of the U near the bight thereof (i. e., remote from the extremities of the legs of the U). Electromagnetic coils 43 and 44 are also wound about the legs of the U-shaped pole piece 40 adjacent their extremities. These latter coils are adapted for energization with horizontal deflection frequency energy of suitable wave shape. It will further be seen that the magnet 30 comprises a U-shaped core member 40', vertical frequency exciter coils 41' and 42' and horizontal frequency exciter coils 43' and 44'. Similarly, the magnet 31 includes a U-shaped pole piece 40'', vertical exciter coils 41'' and 42'' and horizontal exciter coils 43'' and 44''.

Circuitry for energizing the horizontal frequency exciter coils of the magnets 29, 30 and 31 is illustrated in Figure 3 of the drawing wherein reference numerals identical to those employed in Figure 2 designate the same parts. A positive-going pulse 45 of generally rectangular wave shape is applied to the input terminal 46 of the "blue" horizontal convergence circuitry. Pulses such as the one represented by reference numeral 45 may be derived by connecting the terminal 46 directly to a suitable point in the horizontal deflection wave generator 28 such, for example, as the usual horizontal output transformer found in conventional television receivers. The pulse 45 may be of 50 volts amplitude, peak to peak, and is integrated into a generally sawtooth waveshape 48 by the variable inductance 47 connected to the input terminal 46. A shunt path comprising a capacitor 49 and the parallel combination of a variable inductance 50 and resistor 51 serves to shape the wave form 48 further toward a parabolic voltage wave form as indicated at 52. This wave form, when passed through the coils 43 and 44, connected in series-aiding relationship, produces a generally parabolic current waveform 53 in the coils for

producing the required parabolically varying magnetic field between the pole pieces 37 and 38 of the kinescope.

The amplitude of the convergence waveform flowing through the coils 43 and 44 is controlled by the variable series inductance 47, while its tilt or phase (i. e., shift in the minimum amplitude point of the parabolic wave toward the beginning or end of the wave) is controlled by the variable inductance 50. It is to be noted that the waveshaping function is performed, in part, by the inductance of the coils 43, which aids in integrating the sawtooth voltage waveform for the production of the parabolic current waveform 53.

The circuitry for the red and green magnets, insofar as the horizontal frequency waveforms are concerned, is also illustrated in Figure 3. The red and green horizontal convergence circuitry is interconnected for joint energization and control from a single source, indicated by the input terminal 46' which may be connected to a suitable point on the horizontal output transformer. The input pulse 45' is applied via a red-green horizontal amplitude control inductance 47' to the center tap of an inductance 50' which controls the relative amplitude of the sawtooth wave (produced by the integrating action of the inductance 47') applied to the red and green convergence magnets, respectively. The tilt of the parabolic currents applied to the convergence windings is controlled by a resistor 54 designated "Red-green Horiz. Tilt" while the amount of tilting imparted to the two waves is controlled by the "Red-green Tilt Balance" potentiometer 55.

Figure 4 illustrates circuitry in accordance with a specific form of the invention for energizing the vertical frequency exciter coils such as the coils 41 and 42 of the magnet 29. In Figure 4, there is shown a conventional vertical deflection output stage including a vertical deflection wave amplifier 56 whose anode is connected to one end of the primary winding 57 of a deflection output transformer 58. The other end of the primary winding 56 is connected to a source of positive operating potential (+B) indicated at the terminal 59. The screen grid electrode 60 of the amplifier 54 is connected to a source of positive voltage, as indicated. The suppressor grid electrode 61 of the amplifier is conventionally connected to the cathode 62 which, in turn, is connected to a point of reference potential (e. g., ground) through a resistor 63. The amplifier 54 is adapted to receive at its control grid input terminal 64 a conventional spiked sawtooth voltage wave of vertical deflection frequency from a suitable source such as the usual vertical deflection oscillator. The transformer 58 includes a secondary winding 65 connected to the vertical deflection coils of the yoke 26 for applying vertical deflection frequency energy to the latter.

Energization of the vertical frequency exciter coils of the convergence magnets is effected in the following manner: a sawtooth voltage wave shaped generally as indicated by the waveform 66 is derived from the cathode 62 of the vertical deflection output amplifier. This voltage wave, peaked somewhat as shown, is present across the resistor 63 and also across each of a pair of potentiometers 67 and 68, so that a parabolic current wave is automatically applied to the vertical frequency exciter coils such as the coils 41 and 42 of the magnet 29. Thus, a controllable amount of the voltage wave 66 appearing across the resistor 63 is applied via the adjustable tap 71 to one end of the coil 41-42, as illustrated. Similarly, an adjustable tap 72 on the potentiometer 67 applies an adjustable amount of the sawtooth voltage wave to the winding 41'-42' of the magnet 30. A similar connection is made from the potentiometer 68 via a tap to the winding 41''-42'' of the magnet 31.

The vertical frequency convergence circuitry further includes a winding 74 on the transformer 58 in which there is induced a voltage wave such as that indicated at 75, which voltage wave is in the nature of a peaked

sawtooth wave for controlling the tilt of the parabolic waveform to be produced in the coils 41-42 of the magnet 29. The amplitude of the tilt voltage applied to these coils is controlled by the potentiometer 76 whose movable contact 76' is connected to the coils 41-42. Thus, by adjustment of the tap 71 and the contact 76', the amplitude and tilt of the voltage waveform applied to the coils 41-42 may be controlled. The composite voltage waveform resulting from the combination of the waves 66 and 75 is integrated by the inductance of the coils 41-42 to produce therein the generally parabolic current wave 77.

The circuits for energizing the exciter coils of the magnets 30 and 31 with vertical deflection frequency convergence waves are similar to that described in connection with the magnet 29. One difference, however, is that, while the tilt waveform 75 provided by the winding 74 is adjustable only as to magnitude, the tilt waveforms provided by the winding 85 across the potentiometers 86 and 87 for use in the magnets 30 and 31, respectively, are adjustable both as to amplitude and polarity. That is to say, the winding 85 on the transformer 58 is center tapped. Thus, there appear at opposite ends of the vertical green tilt potentiometer 86 and the vertical red tilt potentiometer 87 oppositely polarized waveforms corresponding in shape to the waveform 75 which appears across the potentiometer 76. It will be recognized, therefore, that each of the magnets 30 and 31 will receive both the sawtooth and tilt waves of adjustable amplitude and phase.

In accordance with the present invention, static convergence of the beams 17, 18 and 19 is effected through direct current energization of the magnets 29, 30 and 31. Specifically, the present invention provides means for applying variable direct current energy to the vertical frequency exciter coils of the convergence magnets. While such arrangements have been employed in the past, prior systems have involved separate energization of each of the magnets, so that each of the several electron beams could be moved radially inwardly or outwardly with respect to the longitudinal axis of the tube and independently of each of the other beams. According to the present invention, on the other hand, and as has been stated generally above, static convergence of the electron beams is so controlled that the convergence may be likened to a rectangular coordinate system. The manner in which this novel system of convergence may be realized and specific apparatus for performing this function will become apparent from the remaining circuitry of Figure 4.

In Figure 4, there is illustrated the horizontal deflection output amplifier stage which includes an amplifier tube 90 whose anode 91 is, as shown, adapted for connection to a suitable point on the horizontal deflection output transformer. The control grid input terminal 92 of the amplifier 90 receives a conventional sawtooth wave of horizontal deflection frequency, while the cathode 93 of the amplifier is connected through series potentiometers 94 and 95 to a point of fixed potential (e. g., ground). The potentiometers 94 and 95 are bypassed by a large capacitor 96, so that there is present across the potentiometers 94 and 95 a direct current voltage produced by anode-cathode current flow through the amplifier tube 90. The potentiometer 95 includes a slider tap 97 which is connected to that end of the coils 41"-42" of the magnet 31 which is remote from the end connected to the potentiometer 68 and constitutes means for causing direct current static convergence energy to flow through the coils 41"-42".

Connected across the potentiometer 95 is a potentiometer 98 whose slider tap 99 is ganged to the tap 97 in such manner that the two taps are moved in the same direction through a single control. As will be noted from Figure 4, movement of the taps 97 and 99 in a given direction produces equal amounts of voltage

change to the two taps but of the opposite sense. That is, if the two taps are moved down (as viewed in the drawing), the voltage at the tap 97 will become less positive, while the voltage at the tap 99 will become more positive by the same amount. The tap 99 is connected to the coils 41"-42" at the end remote from the end connected to the potentiometer 67 and serves to cause direct current static convergence energy to flow through the magnet 30. For simplicity of terminology, the potentiometers 95 and 98 will be termed herein the "red-green vertical static convergence control." The reason for this designation is that, by adjustment of the taps 97 and 99, the red and green electron beams 18 and 19, respectively, may be moved simultaneously with respect to the longitudinal axis of the tube along radii thereof and in opposite directions with respect to the axis. That is, if the taps 97 and 99 are adjusted in such direction as to move the beam 18 toward the axis of the tube by a given amount, the beam 19 will be moved away from the axis of the tube by the same amount. When the tube face is viewed, it appears that the vertical spacing between the spots produced by the beams 18 and 19 is changed. Actually, although each of the beams 18 and 19 is moved only along a radius of the tube, the vertical component of such beam movement does indeed produce a change in the vertical spacing between the spots produced thereby. It is this simultaneous movement of the two beams 18 and 19 which is termed hereinabove as a "dual control."

Also connected across the potentiometers 95 and 98 is a potentiometer 100 which will be termed herein the "red-green horizontal static convergence control." The adjustable slider tap 101 of the potentiometer 100 is connected to the center tap 85' of the winding 85 of the transformer 58. It will, therefore, be appreciated that, by virtue of the connection from the potentiometer 100 to the center tap 85, a direct current voltage is produced across the potentiometers 86 and 87 from which the tilt waveforms are applied to the magnets 30 and 31. Movement of the slider tap 101 on the potentiometer 100 affects the two magnets 30 and 31 equally and, specifically, by applying the same direct current voltage to both of the sets of coils 41"-42" and 41"-42". Thus, it will be understood that movement of the tap 101 in a first direction will cause the two beams 18 and 19 to move inwardly toward the axis of the tube by the same amount, while movement of the tap 101 in the opposite direction will cause outward movement of the beams 18 and 19 an equal amount. As viewed on the screen of the tube, such simultaneous movement of the beams 18 and 19 has the effect of altering the horizontal separation of the beam spots, such horizontal separation being a function of the horizontal component of the radial movement of the beams. Hence, it will be recognized that, while the potentiometers 95 and 98 control the vertical spacing between the beam spots produced by the beams 18 and 19, the horizontal separation between the same spots is controlled by the potentiometer 100, so that the spots produced by the beams 18 and 19 may be readily converged at the screen.

The third beam, namely, the blue beam 17, is controlled, insofar as static convergence is concerned, by means of a "blue vertical static convergence" potentiometer 102 whose slider tap 103 is connected via a resistor 104 and a lead 105 to that end of the coils 41-42 remote from the end connected to the potentiometer 76. The potentiometer 102 is, further, center-tapped, the center tap 106 being directly connected to one end of the potentiometer 76. It will be apparent, therefore, that opposite polarities of direct current voltage may be applied to the coils 41-42 by movement of the tap 103 from one side to the other of the center tap 106 of the potentiometer 102, so that the beam 17 may be moved toward or away from the axis of the tube along a radius thereof. By virtue of such movement of the

blue beam 17, that beam may be brought to the same horizontal line as that on which the earlier converged beams 18 and 19 lie. Assuming that the three guns are perfectly located at the apices of an equilateral triangle such that the beams are movable exactly along radii of the tube, the described movement of the beam 17 would bring the spot produced by that beam into coincidence with the spots of the beams 18 and 19.

Actually, however, and in order to correct for departures from such perfect construction, conventional convergence systems further include an element for controlling the lateral positioning of one of the electron beams such, for example, as the blue beam 17. An example of such an element is given in an article by M. J. Obert entitled "Deflection and Convergence of the 21" Color Kinescope" which appeared in the same issue of the RCA Review as the Seelen et al. article. The form of "blue positioning" correcting means shown in the Obert article is a permanent magnet adjustable as to direction and strength. In accordance with the present apparatus, the blue beam positioning means takes the form of an electromagnet 108 of suitable configuration represented diagrammatically in Figure 1. The electromagnet 108 may include a core member (not shown) associated with the tube for producing lateral shifting of the beam 17 when energized by suitable direct current. This energization is afforded by the circuitry of Figure 4 which also includes the potentiometer 94, mentioned above, in series with the static convergence potentiometers 95 and 98. The electromagnetic winding of the magnet 108 is connected to the potentiometer 94, as shown, in such manner that a direct current of reversible direction and variable amplitude may be caused to flow through the winding. In this manner, the blue beam 17 may be brought into convergence with the other two beams.

It has been found that, once the red and green beams of the kinescope have been properly converged in accordance with the procedure set forth above, adjustment of the blue beam controlling magnet 29 through the agency of the potentiometer 106 produces an interaction with the red and green beam convergence magnets 30 and 31. Such interaction is undesirable, since it changes the static convergence fields of the earlier adjusted beams. Hence, in accordance with a further aspect of the present invention, means are provided for substantially eliminating the undesirable effect of the blue beam controlling magnet 29 upon the red and green beam controlling magnets 30 and 31. Such means may take the simple form of a circuit connection indicated as a resistor 110 for applying from the blue beam vertical static convergence controlling potentiometer 102 to the red and green convergence magnets energy of the same magnitude as that applied to the blue magnet 29 but of such sense as to "buck" the effect of the magnet 29 upon the magnets 30 and 31. That is, the resistor 110 is connected from the slider tap 103 on the potentiometer 102 to the center tap 85' of the transformer winding 85. Thus, in addition to the direct current energy applied to the red and green convergence magnets via the center tap connection to the potentiometer 100, there is applied the further direct current from the potentiometer 102 which adds algebraically to the first-named direct current energy and in such manner as to compensate for any undesirable interaction between the blue convergence magnet field and that of the red and green convergence magnets.

It will also be noted that the arrangement of Figure 4 in which the vertical frequency convergence waves are derived from the cathode circuit of the vertical deflection amplifier 56 causes the application of direct current voltage to the several vertical frequency exciter coils of the convergence magnets. This direct current voltage is, for each of the magnets, proportional to the amplitude of the convergence sawtooth wave 66. The application

of this direct current voltage from the convergence wave source to the magnets has the advantageous effect of compensating for what may be termed the "direct current component" of the dynamic convergence waves (i. e., the sum of the direct current components of the vertical and horizontal frequency waves) applied to the magnet. That is to say, it has been found that when the beams of a kinescope such as the type in question have been statically and dynamically converged, if the dynamic convergence energy is removed from the convergence magnets, the beams tend to be converged nearer the edges of the screen rather than at the center thereof. By virtue of the fact that the several vertical frequency convergence waves are derived from resistors in the cathode circuit of the vertical deflection amplifier, each such wave applied to a convergence magnet is accompanied by direct current of equal magnitude but opposite sense from the direct current component of the convergence wave, whereby the direct current component of the wave is effectively compensated. In the illustrated circuit, the amplitude of vertical frequency convergence wave required for the blue beam may, in specific instances, be quite small. In such event, a separate source of direct current may be provided for the blue convergence winding to furnish the requisite amount of direct current compensation for that beam.

It will be recognized by those skilled in the art that the apparatus of the present invention lends itself to "setting up" the convergence in a three beam color kinescope with a cross-hatch pattern of horizontal and vertical bars. That is, video signals representative of such a pattern may be applied to the several beams such that, when the beams are properly converged, the image produced on the kinescope screen is that of a black and white cross-hatch pattern. A simple static convergence set-up procedure which may be followed when using such a cross-hatch pattern is as follows:

(1) Adjust the "red-green vertical static convergence control" (potentiometers 95 and 98) until the associated red and green horizontal bars of the pattern are coincident.

(2) Adjust the lateral static convergence component via potentiometer 94 until a given blue vertical bar lies mid-way between its associated red and green vertical bars.

(3) Adjust the "red-green horizontal static convergence control" (potentiometer 100) until the associated red and green vertical bars are coincident.

(4) Adjust the "blue vertical static convergence control" (potentiometer 102) until the blue horizontal bar is coincident with its associated red and green horizontal bars.

While the present invention has been described herein in accordance with an illustrative embodiment wherein the vertical static convergence action involves the use of the cross-connected potentiometers 95 and 98 whereby, through the agency of a single control, the direct current energy applied to the red magnet, for example, is increased as the direct current energy applied to the green magnet is decreased (and vice versa), a similar beam controlling action may be realized in other manners. For example, while the vertical frequency exciter coils of the magnets 29, 30 and 31 described herein are assumed to be wound in the same direction, and energized in the same direction, the windings of the coils 41'-42' may be reversed with respect to the direction of winding of the coils 41"-42", in which case both of the two magnets could be energized from a single potentiometer, insofar as vertical static convergence is concerned, since the desired "differential" movement of the red and green beams would be afforded from the single potentiometer. That is, assuming an increased direct current voltage is applied to the two magnets whose coils are oppositely wound, one of the beams would be moved toward the center or axis of the tube, while the other

beam would be moved farther from the axis of the tube. A decrease in the direct current voltage applied to the magnets would, on the other hand, move the beams in the opposite directions. Where this latter type of arrangement is employed, however, the horizontal static convergence control would involve the use of an arrangement such as the cross-connected potentiometers 95 and 98 for moving the red and green beams in the same direction with respect to the center of the tube (i. e., both moved toward the center or both moved away from the center). Also, this second arrangement would require the reversal of phase of the vertical frequency convergence and tilt waves applied to one of the magnets, so that the dynamic convergence action would remain in the proper sense.

Having thus described our invention, what we claim as new and desire to secure by Letters Patent is:

1. In a cathode ray tube image-reproducing system wherein a plurality of electron beam components, which traverse pre-deflection paths spaced respectively about the horizontal axis of the tube are angularly deflected by horizontal and vertical beam deflection apparatus to scan a raster at a target electrode, the combination comprising: a plurality of beam convergence structures respectively mounted adjacent to such pre-deflection paths, each of said structures being arranged to effect radial movement of its associated beam component; a source of direct current static convergence energy; and adjustable means including a potentiometer for applying energy from said source in inverse relationship to first and second ones of said structures, said adjustable means and said first and second structures being operatively connected in such manner that, for a given adjustment thereof, the energy supplied to said first structure is decreased while the energy supplied to said second structure is increased whereby the beam component acted upon by said first structure is moved away from the axis of said tube while the beam component acted upon by said second structure is moved toward the axis of said tube, both of said movements being along radii of said tube.

2. In a cathode ray tube image-reproducing system wherein a plurality of electron beam components, which traverse pre-deflection paths spaced respectively about the horizontal axis of the tube are angularly deflected by horizontal and vertical beam deflection apparatus to scan a raster at a target electrode, the combination comprising: a plurality of beam convergence field producing structures respectively mounted adjacent to such pre-deflection paths, each of said structures being arranged to effect radial movement of its associated beam component; a source of direct current static convergence energy; adjustable means for applying energy from said source to first and second ones of said structures, said adjustable means and said first and second structures being operatively connected in such manner that, for a given adjustment thereof, the field produced by said first structure is varied in one sense so that the beam component acted upon by said first structure is moved away from the axis of said tube while the field produced by said second structure is varied in the opposite sense so that the beam component acted upon by said second structure is moved toward the axis of said tube, both of said movements being along radii of said tube; and means operatively connected to said first and second structures for applying direct current energy to said structures in the same sense and in such manner as to move the beam components controlled thereby in unison along said radii and in the same direction with respect to the axis of said tube.

3. In a cathode ray tube image-reproducing system wherein a plurality of electron beam components, which traverse pre-deflection paths spaced respectively about the horizontal axis of the tube, are angularly deflected by horizontal and vertical beam deflection apparatus to scan a raster at a target electrode, the combination

comprising: a plurality of beam convergence field producing structures respectively mounted adjacent to such pre-deflection paths, each of said structures being arranged to effect radial movement of its associated beam component; a source of direct current static convergence energy; and adjustable means for applying energy from said source to first and second ones of said structures to energize said first and second structures in inverse relationship, said adjustable means being of such character that, for a given adjustment thereof, the direct current energy applied to said first structure is increased while the direct current energy applied to said second structure is decreased.

4. In a cathode ray tube image-reproducing system wherein a plurality of electron beam components, which traverse pre-deflection paths spaced respectively about the horizontal axis of the tube are angularly deflected by horizontal and vertical beam deflection apparatus to scan a raster at a target electrode, the combination comprising: a plurality of beam convergence field producing structures respectively mounted adjacent to such pre-deflection paths, each of said structures being arranged to effect radial movement of its associated beam component; a source of direct current static convergence energy; adjustable means for applying energy from said source to first and second ones of said structures, said adjustable means and said first and second structures being operatively connected in such manner that, for a given adjustment thereof the field produced by said first structure is varied in one sense so that the beam component acted upon by said first structure is moved away from the axis of said tube while the field produced by said second structure is varied in the opposite sense so that the beam component acted upon by said second structure is moved toward the axis of said tube, both of said movements being along radii of said tube; adjustable means for applying direct current static convergence energy to a third one of said structures, energization of said third structure having an interacting effect upon the fields produced by said first and second structures; and means connected between said last-named means and said first and second structures for applying to said first and second structures direct current energy of such amplitude and sense as to compensate for the effect of said third structure upon the fields produced by said first and second structures.

5. In a cathode ray tube image-reproducing system wherein first, second and third electron beams, which traverse pre-deflection paths spaced respectively about the horizontal axis of the tube are angularly deflected by horizontal and vertical beam deflection apparatus to scan a raster at a target electrode, the combination comprising: first, second and third beam convergence magnet structures respectively mounted adjacent to such pre-deflection paths, each of said structures being arranged to effect radial movement of its associated beam; a source of direct current static convergence energy; adjustable means for applying energy from said source to first and second ones of said structures for causing each of said first and second structures to produce a magnetic field, said adjustable means and said first and second structures being operatively connected in such manner that, for a given adjustment thereof, the beam acted upon by said first structure is moved away from the axis of said tube while the beam acted upon by said second structure is moved toward the axis of said tube, both of said movements being along radii of said tube; means for energizing said third magnet structure with direct current energy to cause it to produce a magnetic field for moving said third beam along a radius of such tube, there being undesirable interaction between said last-named field and the fields produced by said first and second structures; and means operatively connected between said last-named energizing means and said first and second structures for applying to said first and second structures direct current energy of such

magnitude and sense as to counteract such undesirable interaction.

6. In a cathode ray tube image-reproducing system wherein a plurality of electron beam components, which traverse pre-deflection paths spaced respectively about the horizontal axis of the tube, are angularly deflected by horizontal and vertical beam deflection apparatus to scan a raster at a target electrode, the combination comprising: a plurality of beam convergence structures respectively mounted adjacent to such pre-deflection paths, each of said structures being arranged to effect radial movement of its associated beam component; a source of direct current static convergence voltage energy, and adjustable means for applying energy from said source to first and second ones of said structures, said adjustable means comprising first and second potentiometers having adjustable contact members ganged for movement in unison and in the same direction, one of said contact members being connected to said first structure and the other of said

contact members being connected to said second structure, and means connecting said potentiometers to said source in opposite sense with respect to each other, such that, for a given adjustment of said contact members, the direct current energy applied to said first structure is increased while the direct current energy applied to said second structure is decreased.

7. The invention as defined by claim 6 including a third potentiometer connected across said source and having an adjustable output terminal, and means for applying energy from said terminal to said first and second structures in the same sense.
